UNITED STATES PATENT OFFICE

139,087

DESIGN FOR A BABY RATTLE

Eoina Nudelman, Chicago, Ill.

Application May 16, 1944, Serial No. 113,605

Term of patent 7 years

(Cl. D34—15)

To all whom it may concern:

Be it known that I, Eoina Nudelman, a citizen of France, residing at Chicago, in the county of Cook and State of Illinois, have invented a new, original, and ornamental Design for Baby Rattles, of which the following is a specification, reference being had to the accompanying drawing, forming part thereof.

Fig. 1 is a front elevational view of a baby rattle, showing my new design;

Fig. 2 is a side view of the same; and

Fig. 3 is a rear elevational view.

I claim:

The ornamental design for a baby rattle, as shown.

Eoina Nudelman.
